UNITED STATES PATENT OFFICE.

WELLINGTON P. KIDDER, OF BOSTON, MASSACHUSETTS.

SAFETY DEVICE FOR ELEVATORS.

SPECIFICATION forming part of Letters Patent No. 514,123, dated February 6, 1894.

Application filed May 15, 1893. Serial No. 474,327. (No model.)

To all whom it may concern:

Be it known that I, WELLINGTON P. KIDDER, a citizen of the United States of America, residing at Boston, in the county of Suffolk and State of Massachusetts, have invented certain new and useful Improvements in Safety Devices for Elevators, of which the following is a specification, reference being had therein to the accompanying drawings.

10 This improvement is designed principally to provide a safety fastening for the gates or doors of freight elevators, which fastener is so constructed and arranged that the rope for operating the valve cannot be operated while 15 the door is open; and the door cannot be opened unless the car is at rest.

To this end the invention consists in the devices hereinafter described in connection with the appended drawings and then defi- 20 nitely claimed at the end hereof.

In the accompanying drawings—Figure 1 is a front view of the gates of a freight elevator with the gates closed. Fig. 2 is a similar view with the gates open. Fig. 3 is a horizontal section on the line xx of Fig. 1. Fig. 4 is a similar section on the line yy of Fig. 2. Fig. 5 is a side view of the locking device. Fig. 6 is a front view of a modification with the gates closed. Fig. 7 is a similar view of 30 the same device with the gates open. Fig. 8 is a plan of the same. Fig. 9 is a side view of the same.

Referring now to the details of the drawings by letter, and more particularly to Figs. 1 to 5, A represents the well gate, which I prefer to make in two sections as shown, connected by ropes B passing over pulleys C so that one section counterbalances the other—the lower one sinking down even with or just 40 below the level of the floor, as shown in Fig. 2. At the side are bolted two brackets D, supporting two rods E, on which slides a block F, which is made fast in any suitable manner to the companion or valve controlling rope G, 45 which I prefer to call a "controller." On these brackets D, is pivoted at d , a peculiarly shaped bar or fastener H, provided with a recess or bend h , whose shape is clearly shown at Fig. 5, which bar, being pivoted as de- 50 scribed and shown, is capable of swinging sidewise, so as to assume either the position

indicated by Figs. 1 and 3, or that shown in Figs. 2 and 4.

Each section of the gate is provided with a short bar J, which projects into the path of the bend or recess h , as the bar H swings on the pivots d .

The operation is as follows: Supposing the sections of the gate to be open as shown in Fig. 2, the block F on the rope will be in the recess h and so the rope or controller cannot be moved sufficiently to start the car, and any attempt to move the bar H will be prevented by the body of said bar H coming in contact with the bars J, so that the car cannot possibly be started while the sections of the gate are in the position shown in Figs. 2 and 4. If now the sections of the gate are closed so as to bring the bars J opposite the recess h , the bar H may readily be swung over 65 the bars J, which will thus securely fasten the gate and at the same time swing away from the block F, thus leaving the rope free to move and start the car as soon as the gate is closed and fastened. When the rope or controller has been moved to start the car, 70 the block F assumes either the position indicated by full lines in Fig. 1 or that in dotted lines in the same figure, according to the direction the car is moving, and when in either 75 of these positions as it abuts against the body of the bar H, the latter cannot be moved, and so the sections of the gate are held fast until the car is again made stationary, when the block F is again opposite the recess h (as in 80 Fig. 2) when the sections of the gate can be readily opened.

In the modifications shown in Figs. 6 and 7, there is an elbow lever K pivoted to each bracket D, and the two levers are connected together by a rod L, so as to move simultaneously. Pivotally connected to the opposite ends of the levers is a bar H' having a recess h' for the same purpose as the recess h in the bar H. It is obvious that as the bar H' moves 90 with the elbow levers K said bar will move sidewise and over the bars J or block F in substantially the same manner as the bar H in Figs. 1 to 5. In either of these forms of my invention, the gate may be made in two sections or 95 in one, as preferred.

I do not intend to limit myself to the de-

vices herein shown, as other modifications may be adopted without departing from the spirit of my invention.

What I claim as new is—

- 5 1. The combination in an elevator and with the car and the controller thereof, the latter having a projection fast thereon, of a laterally moving bar disconnected from the car and engaging with such projection, and a vertically-movable gate arranged to hold the bar in engagement with the projection on the controller when said gate is open, substantially as described.
- 10 2. The combination in an elevator and with the car and vertically-movable well-gate thereof, of a laterally moving bar, disconnected from the car and engaging with the gate, and a controller provided with a projection arranged to hold the bar in engagement with the well-gate when the car is in motion, substantially as described.
- 15 3. The combination in an elevator and with the car and the controller, the latter having a projection thereon, of a laterally-movable bar adapted to engage with the projection on the gate when said gate is closed, and with the projection on the controller when the gate is open, substantially as described.
- 20 4. The combination in an elevator and with the car, the controller, and the well-gate thereof, of a bar J mounted on the gate, a block F mounted on the rope, and a laterally moving bar engaging with the block F when the gate is open and with the bar J when the gate is closed, substantially as described.
- 25 5. The combination in an elevator and with

the car, the valve operating device and the well-gate thereof, of a bar J mounted on the gate, a block F mounted on the rope, and a vibrating pivoted bar H having a recess *h* constructed and arranged to pass over and hold the block F when the gate is open, and the bar J when the gate is closed, substantially as described.

6. The combination in an elevator and with the well, the car, the operating apparatus, the double gate A and the rope for setting the operating apparatus in motion, of a block F attached to said rope, the bars J on the sections of the gate, and the pivoted bar H having the recess *h* arranged to pass over and hold the bar J when the gate is closed and the block F when the gate is open, substantially as described.

7. The combination in an elevator and with the well, the car, the valve operating device and the well gate, of the brackets D, the rods E supported by said brackets, the block F sliding on said rods and attached to the valve operating device, a bar J on said well gate, and the bar H having a recess *h* and pivoted on the brackets D, and co-operating with the bar J and block F, substantially as described and for the purpose set forth.

In testimony whereof I affix my signature, in presence of two witnesses, this 12th day of May, 1893.

WELLINGTON P. KIDDER.
